STAPLE FEED MECHANISM FOR FASTENER
APPLYING INSTRUMENTSOtto Attula, Woodside, N. Y., assignor to Lou
Obstfeld, Brooklyn, N. Y., and Abraham Obst-
feld, New York, N. Y.

Application May 31, 1941, Serial No. 395,983

13 Claims. (Cl. 1—49)

This invention relates to fastener applying instruments of the magazine type, and more particularly to the feed mechanism for such fasteners.

The primary object of my invention is to generally improve fastener applying instruments of the type in which a bar of staples is automatically fed by means of a spring-operated pusher toward a staple driving blade. The fastener applying instrument is of the rear-loading type, and the feed mechanism is accordingly made removable. It comprises a staple pusher, a rod slidably receiving the pusher, a feed spring coiled about the rod, and a pusher locked affixed to the rear end of the rod. One object of the present invention is to improve the pusher lock and to make the same openly accessible and readily releasable. Another object is to facilitate loading the machine with staples, and for this purpose the staple core may be projected beyond the rear end of the frame of the machine, the projecting end preferably being housed and concealed by the aforesaid pusher lock. Still another object is to facilitate replacement of the feed mechanism by preventing rotation of the pusher and the pusher lock relative to the aforesaid rod, the pusher being keyed to the rod by tapered or wedge-shaped keys which insure automatic engagement of the parts in keyed relation.

To the accomplishment of the foregoing and such other objects as will hereinafter appear, my invention consists in the elements of the fastener applying instrument and their relation one to the other, as hereinafter are more particularly described in the specification and sought to be defined in the claims. The specification is accompanied by a drawing, in which:

Fig. 1 is a section taken in elevation through a fastener applying instrument embodying features of my invention, (the upwardly turned edges of the sides of the machine being cross-hatched for clarity, as though the section were somewhat off true center line);

Fig. 2 shows the rear end portion of the machine in elevation;

Fig. 3 is a horizontal section taken in the plane of the line 3—3 of Fig. 2;

Fig. 4 is a similar view (with only part of the pusher lock broken away), but showing how the sides of the pusher may be pressed together to release the detents;

Fig. 5 is a side elevation showing replacement of the staple pusher after loading the machine with staples;

Fig. 6 illustrates the keyways on the pusher for receiving the keyed end of the rod;

Fig. 7 is a plan view of the keyed end of the rod;

5 Fig. 8 is a side elevation of the keyed end of the rod;

Fig. 9 is a transverse section through the staple magazine with the feed mechanism removed;

10 Fig. 10 is a plan view of the rear end of the fastener applying instrument, corresponding substantially to the part of the machine shown in Fig. 2; and

15 Fig. 11 is a partial section through the rear end portion of a machine having a modified pusher lock.

Referring to the drawing, and more particularly to Fig. 1, the complete fastener applying instrument comprises a frame 12, part of which 20 constitutes a grip 14. The frame consists of sides having edges bent toward one another to form a structure which is enclosed except at the bottom, where appropriate staple magazine parts are inserted; and at the forward and rear ends of the staple magazine, the latter being readily openable for rear loading of staples, and the forward end being openable for servicing and for the relief of staple jams. In the present case, the fastener applying instrument is a tacker, and no anvil or staple clincher is provided.

The machine is operated by means of a handle 16 pivoted at 18, and carrying a pawl 20. The staples are driven by a staple driving blade 22 secured to a plunger 24 urged downwardly by a main drive spring 26. Leather inserts 28 and 29 may, if desired, be provided at the top of spring 26 and beneath plunger 24. When handle 16 is depressed, the spring 26 is compressed until pawl 20 reaches and bears against a pawl release pin 30 which moves the pawl rearwardly and so releases the plunger for descent, at which time it drives the endmost one of a bar of staples 32 out of the machine. When handle 16 is released, it is raised by a restoring spring 34, and the upward motion may be limited by a stop 36 secured to and forming a part of handle 16.

50 The staple magazine comprises a staple core 38 which is dimensioned to slidably receive the staples. The rear end 40 of the staple core projects beyond the open rear end 42 of the frame, and is preferably tapered as shown, in order to facilitate the staple-loading operation. The staple core 38 is properly spaced from the sides

44 and 46 of the frame, by means of narrow strips of metal or liners 48 (Fig. 9). The staple magazine is completed by means of a channel-shaped top guide 50 which is secured between the sides of the frame above the staple core, the bottom edges of the side walls 52 of the channel being disposed close to the top of staple core 38, as is indicated at 54, thus forming a guide for accurately receiving the staples and staple pusher. The rear end of the top guide 10 may be tapered, as is indicated at 55 (Fig. 1), thereby facilitating the loading of staples into the magazine.

The staple feed mechanism comprises a channel-shaped staple pusher 56 having a cross-section substantially the same as that of the staples being fed through the magazine. A U-shaped part 58 is secured to the top of the pusher, as by means of spot-welding, said part being apertured to receive a pusher rod 60. A compression feed spring 62 is coiled about the rod 60, and acts to normally urge the pusher forwardly on the rod, as will be clear from inspection of Fig. 1 and comparison of that figure with Fig. 5. A pusher lock 64 is secured at the rear end of rod 60. This lock has side walls 66 which may be bent together from the normal position shown in Fig. 3, to the compressed position shown in Fig. 4.

The side walls 66 of the pusher lock are received partially within or partially overlap the side walls 44 and 46 of the frame. Specifically, tabs 68 project forwardly from side walls 66, and these tabs are provided with means to mate with and lock within the side walls of the frame. In the present case the tabs 68 are provided with outwardly struck detents 70 which fit into recesses or slots 72 formed in the side walls 44 and 46. The leading edges 74 of the tabs 68 are preferably turned inwardly so that the tabs may be readily pushed between the side walls of the frame when the feed mechanism is being restored to the machine. During operation of the machine, the pusher lock is held in the position shown in Figs. 1, 2, 3 and 10, but whenever desired, as when reloading the machine, it is only necessary to squeeze the exposed sides 66 together, as shown in Fig. 4, in order to disengage the mating detent means, thereby releasing the lock for removal from the machine together with the rod 60 and pusher 56.

The pusher lock is preferably made in the form of a housing, in order to enclose and conceal the projecting rear end 40 of the staple core. In the present case, the housing is formed of a single piece of sheet metal having an end wall 76 to which the pusher rod is riveted. In the specific structure shown, a collar or fitting 78 is riveted to end wall 76, as is best shown in Figs. 1 and 3, and the rod 60 is received within and preferably fixed to the fitting 78, as by means of a force-fit, spot-welding, or the like. The side walls 66 previously referred to are bent forwardly from the end wall 76. A top wall 80 is bent forwardly from end wall 76, but the side walls 66 are kept free of the top wall 80, as is best shown in Fig. 2, in order not to interfere with compression of the side walls toward one another. It will be seen that the side walls, top wall and end wall form a housing which fits flush against and closes the open rear end 42 of the frame, and forms an apparent continuation of the frame, as will be seen from inspection of Figs. 1, 2 and 10 of the drawing. The housing 64 encloses and conceals the projecting staple

core end 40. The bottom of the housing is, in this particular case, left open, because it rests against a bottom plate 82 which is secured to the bottom of the staple core, as by means of screws, not shown in the drawing. Plate 82 forms a part of a staple remover 84, the end 84 preferably being turned upwardly somewhat and sharpened so that it can be forced under the top of a mistakenly located staple. The bottom of core end 40 is recessed to receive the plate 82 so that the entire bottom of the machine is flush.

In order to facilitate squeezing the sides of the pusher lock together, these sides may be provided with outwardly pressed rounded surfaces or buttons 86.

It is helpful when restoring the staple pusher to the machine, if the pusher can be controlled against turning on the rod. The pusher lock 64 is likewise secured to the rod, so that it may be used as a handle for turning and guiding the pusher when replacing it in the machine. To prevent relative rotation of the pusher and the rod, the forward ear of member 58 is preferably provided with keyways indicated at 88 in Fig. 6. The forward end of the pusher rod is preferably struck or excised to form sidewardly projecting keys 90. These are preferably made tapered when viewed in side elevation, as in Fig. 8, and also when viewed in plan, as in Fig. 7. The tapered or pointed ends 92 of the keys insure their entry into the keyways 88. The large ends of the keys are made substantially larger than the keyways, and thus act as stop means to prevent the feed spring from urging the pusher entirely off the rod.

In Fig. 11, I show a modified pusher lock in which the pusher is held in position by means of a single detent at the top of the pusher, instead of two detents at the sides of the pusher. Referring to that figure, the pusher 64' is a sheet metal housing formed of a single piece of sheet metal much as previously described, it having an end wall 76' to which the pusher rod is riveted at 78'. It further comprises side walls 94 which are bent forwardly from the end wall 76', and a top wall 96 which is also bent forwardly from end wall 76'. In the present case the top wall 96 is preferably dimensioned to fit within the side walls 94, so as to be compressible therebetween. (This is analogous to pusher 64, in which the side walls 66 are located beneath the top wall 80, so that they may be squeezed together without interference by the top wall.)

The top wall 96 extends forwardly to come beneath the rearmost portion 98 of the frame. The overlapping parts are provided with mating means, specifically a detent 100 received in a slot 102. The forward tip 104 of the top wall or tab 100 projecting forwardly therefrom is preferably turned downwardly so as to fit readily beneath the frame wall 98. A circular area of the top wall 96 is preferably pressed outwardly to form a convex button 108 which facilitates depression of the top wall, from the locked position 104' shown in broken lines, to the released position 104, shown in solid lines, preparatory to removal of the staple-pushing mechanism.

It is believed that the construction and method of use of my improved feed mechanism, as well as the advantages thereof, will be apparent from the foregoing detailed description thereof. The improvement may be used with a stapling machine, that is, one having a clincher as well as with a tacker, as here shown. It will also be apparent that while I have shown and described

my invention in several preferred forms, changes and modifications may be made in the structures disclosed, without departing from the spirit of the invention as sought to be defined in the following claims.

I claim:

1. Staple feed mechanism for a magazine type of fastener applying mechanism having side walls, said mechanism including a staple pusher, a pusher spring, and a pusher lock at the rear end of said spring, said lock comprising side walls which partially overlap the side walls of the instrument, and mating detent means formed on said overlapping side walls, the arrangement being such that the lock may be secured in position by simply pushing it into place, and may be removed by pressing the exposed sides of the lock together in order to release the mating detent means.

2. Staple feed mechanism for a magazine type of fastener applying instrument having side walls, said mechanism including a staple pusher, a pusher spring, and a pusher lock at the rear end of said spring, said lock comprising side walls which are received partially within the side walls of the instrument, and mating detent means formed on said overlapping side walls, the arrangement being such that the lock may be secured in position by simply pushing it into place, and may be removed by pressing the exposed sides of the lock together in order to release the mating detent means.

3. Staple feed mechanism for a magazine type of fastener applying instrument having side walls, said mechanism including a staple pusher, a rod slidably receiving said pusher, a pusher spring coiled about said rod, and a pusher lock at the rear end of said rod, said lock comprising an end wall to which the rod is secured and side walls bent forwardly from and formed integrally with said end wall, said side walls being received partially within the side walls of the instrument, and mating detent means formed on the overlapping side walls, the arrangement being such that the lock may be secured in position by simply pushing it into place, and may be removed by pressing the exposed sides of the lock together in order to release the mating detent means.

4. Staple feed mechanism for a magazine type of fastener applying instrument having side walls, said mechanism including a staple pusher, a rod slidably receiving said pusher, a pusher spring coiled about said rod, and a pusher lock at the rear end of said rod, said lock comprising an end wall to which the rod is secured and side walls bent forwardly from and formed integrally with said end wall, detents formed on said side walls and dimensioned to be received within the adjacent side walls of the instrument, said instrument walls having mating recesses to receive said detents, the arrangement being such that the lock may be secured in position by simply pushing it into place, and may be removed by pressing the exposed sides of the lock together in order to release the detents from the recesses.

5. In a fastener applying instrument comprising a frame including side walls open at the rear end, a feed mechanism including a staple pusher, a feed spring, and a pusher lock mounted at the rear end of said spring, said pusher lock comprising a piece of sheet metal bent to form a housing open at the forward end and dimensioned to close the open rear end of the frame, tabs projecting forwardly from the sides of the housing

to be received within the sides of the frame, and mating detent means formed on the sides of the frame and tabs for holding the parts together, said detent means being releasable by pressing together the sides of the housing.

6. In a fastener applying instrument comprising a frame including side walls open at the rear end, a feed mechanism including a staple pusher, a feed spring, and a pusher lock mounted at the rear end of said spring, said pusher lock comprising a piece of sheet metal bent to form a housing open at the forward end and dimensioned to close the open rear end of the frame, the sides of said housing being pressed outwardly to form buttons which facilitate squeezing the sides of the housing together, tabs projecting forwardly from the sides of the housing to be received within the sides of the frame, and mating detent means formed on the sides of the frame and tabs for holding the parts together, said detent means being releasable by pressing together the sides of the housing.

7. In a fastener applying instrument comprising a frame including side walls open at the rear end, a feed mechanism including a staple pusher, a rod slidably receiving said pusher, a feed spring coiled about said rod, and a pusher lock mounted at the rear end of said rod, said pusher lock comprising a piece of sheet metal bent to form a housing which is closed at the rear end and open at the forward end and dimensioned to close the open rear end of the frame, said rod being secured to the closed rear end of the housing, the sides of the housing being dimensioned to be received partially within the sides of the frame, and mating detent means formed on the overlapping sides of the frame and tabs for holding the parts together, said detent means being releasable by pressing together the exposed sides of the housing.

8. In a fastener applying instrument comprising a frame including side walls open at the rear end, a staple core disposed in said fastener and having a rear end which projects beyond the sides of the fastener to facilitate the loading of staples in the machine, a feed mechanism including a staple pusher, a rod slidably receiving said pusher, a feed spring coiled about said rod, and a pusher lock mounted at the rear end of said rod, said pusher lock comprising a piece of sheet metal bent to form a housing open at the forward end and dimensioned to be received over and to enclose the exposed rear end of the staple core, the sides of the housing being dimensioned to be received partially within the sides of the frame, and mating detent means formed on the overlapping sides of the frame and housing for holding the parts together, said detent means being releasable by pressing together the exposed sides of the housing.

9. In a fastener applying instrument comprising a frame including side walls open at the rear end, a staple core disposed in said frame and having a rear end which projects beyond the sides of the frame to facilitate the loading of staples in the machine, a feed mechanism including a staple pusher, a rod slidably receiving said pusher, a feed spring coiled about said rod, and a pusher lock mounted at the rear end of said rod, said pusher lock comprising a piece of sheet metal bent to form a housing open at the forward end and dimensioned to be received over and to enclose the exposed rear end of the staple core, the sides of said housing being pressed outwardly to form buttons which facilitate squeezing

the sides of the housing together, tabs projecting forwardly from the sides of the housing to be received within the sides of the frame, and mating detent means formed on the sides of the frame and tabs for holding the parts together, said detent means being releasable by pressing together the sides of the housing or pusher lock.

10. Staple feed mechanism for a fastener applying instrument, said mechanism comprising a pusher, a round rod slidably receiving said pusher, a feed spring coiled about said rod for urging the pusher forwardly, and means to fix the pusher against rotation on the rod when the pusher is removed from the instrument, said means including keyways formed on the pusher and keys formed at the end of the rod, said keys being tapered or wedge-shaped with the large end of the wedge toward the forward end of the rod and the pointed end of the wedge toward the rear end of the rod, whereby said keys readily move into said keyways, yet said pusher cannot leave the rod entirely.

11. Staple feed mechanism for a fastener applying instrument, said mechanism comprising a pusher, a round rod slidably receiving said pusher, a feed spring coiled about said rod for urging the pusher forwardly against the staples, a pusher lock non-rotatably secured to the rear end of said rod, and means to fix the pusher against rotation on the rod when the pusher is removed from the instrument, said means including keyways formed on the pusher and keys formed at the end of the rod, and said keys being tapered or wedge-shaped with the large end of the wedge toward the forward end of the rod and the pointed end of the wedge toward the rear end of the

rod, whereby said keys readily move into said keyways, yet said pusher cannot leave the rod entirely.

12. In a fastener applying instrument comprising a frame which is open at the rear end, a feed mechanism including a staple pusher, a feed spring, and a pusher lock at the rear end of said spring, said pusher lock comprising a piece of sheet metal bent to form a housing open at the forward end and dimensioned to close the open rear end of the frame, a wall of said housing projecting forwardly to overlap a wall of the frame, and mating detent means formed on the overlapping parts of the frame and housing walls for holding the pusher lock and the frame together, said detent means being releasable by pressing an exposed part of the housing wall.

13. In a fastener applying instrument comprising a frame which is open at the rear end, a feed mechanism including a staple pusher, a feed spring, and a pusher lock at the rear end of said spring, said pusher lock comprising a piece of sheet metal bent to form a housing open at the forward end and dimensioned to close the open rear end of the frame, a wall of said housing projecting forwardly to be received within a wall of the frame, the exposed part of said housing wall being pressed outwardly to form a convex button to facilitate squeezing the housing wall away from the frame wall, and mating detent means formed on the overlapping parts of the frame and housing walls for holding the pusher lock and the frame together, said detent means being releasable by pressing the aforesaid button.
